(57) **CLAIM**

The ornamental design for a jog dial, as shown and described.

DESCRIPTION

FIG. 1 is an isometric view of a jog dial incorporating my new design, viewed from above, in front of, and from the right side of the jog dial;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front side elevation view thereof; and,

FIG. 7 is a rear side elevation view thereof.

The broken lines in the drawings are for illustrative purposes only and form no part of the claimed design.
